UNITED STATES PATENT OFFICE.

KARL PETSCHENIG, OF VIENNA, AUSTRIA, ASSIGNOR TO C. P. GOERZ OPTISCHE AN-
STALT, AKTIENGESELLSCHAFT, AKCIOVA SPOLECNOST K. P. GOERZ OPTICKY USTAV,
OF BRATISLAVA, CZECHOSLOVAKIA.

BREECH SIGHT FOR ORDNANCE AND MACHINE GUNS.

Application filed December 5, 1925, Serial No. 73,370, and in Germany December 15, 1924.

This invention relates to breech sights for ordnance and machine guns. The total elevation at any time required, for which such sights have to be adjusted, more particularly 5 in firing on targets covered from sight, is in general the sum of two angles, the ground angle, and the firing angle; and the object of my invention is to so construct the breech sight that the adjustment for each of these 10 angles can be made rapidly and separately.

This is realized according to the present invention by positively connecting the sight telescope carrier, provided with a longitudinal and transverse water level, with a 15 worm wheel sector rotatable around a horizontal axis at right angles to the sight line. Into the teeth of which sector engages a worm, rotatable by means of a handle disc. The angle through which the said worm has 20 been turned may be read on a circular scale secured to the handle disc, by means of a pointer mounted on a sleeve rotatable around the worm spindle. This sleeve is held fast on the worm spindle by a releasable frictional clutch, the rotation relatively to the 25 carrier secured to the fire arm, being read on a second circular division. An embodiment of the invention as applied to a machine gun is illustrated by way of example in the annexed drawings.

Fig. 1 is a side elevation partly in longitudinal section, Fig. 2 is a plan view,

Fig. 3 is the main transverse section,

Fig. 4 is a transverse section through the 35 ground angle scale drum on the line 4-4 Fig. 1; Fig. 5 is a transverse section of the firing angle scale drum on the line B, B Fig. 1 and

Figs. 6 and 7 are a longitudinal section 40 and a plan view respectively, of another constructional form of the scale drum or sleeves with an automatic locking device. Fig. 6^a is a fragmentary view on line 6^a-6^a of Fig. 6.

The yoke 2 secured to the machine gun 1 carries in a socket at right angles to the axis of the bore, a journal pin 3 rotatable in this socket on which is mounted a worm wheel sector 4 secured to the telescope carrier F. Into the teeth of the worm wheel sector rotatably journaled in a casing 2^a mounted on the yoke, there engages a worm 5 to the square end 5^a of which a handle disc 6 is secured. This handle disc is pro-

vided with a circular scale 6^a and carries on its stepped part a screw thread 6^b into which engages a sector of a nut 7, which on turning the handle disc moves in the longitudinal slot of a drum or sleeve 8 concentric to the worm 5, so that each full revolution of the 60 worm may be read by means of a mark 7^a provided on the nut sector 7, on a scale 8^a provided on both sides of the longitudinal slot, while each fraction of a complete revolution of the worm may be exactly read on 65 the circular scale 6^a, by means of a mark 8^c provided on the edge 8^b of the handle disc. In view of the fact that this drum 8 is rotatable, it is preferable, for facilitating the reading, that three of such slots carrying 70 scales be provided at distances of 120° and also three marks. The drum 8 is provided at its right hand end with a helical groove 8^d into which engages a nut sector 9, which latter is movable axially only, in a longitudinal slot of a tubular extension 10 mounted on the worm sector casing 2^a by turning the drum 8 by means of its grasping edge 8^b. This nut sector 9 too, is provided with a mark 9^a, indicating the extent to which the 75 sleeve has been turned, on a scale 8^e engraved between the turns of the helical groove. The right hand end of the drum 8 is provided with a concentric threaded bore into which, after a pressure spring 11 has 80 been inserted thereinto, the threaded ring 12 is screwed. This ring is provided on its 85 annular face with fine radial teeth, Z (Fig. 1) which teeth engage, under the action of the spring 11 with nicely fitting teeth on the 90 ring 13, secured to the worm spindle and serving at the same time as its journal pin, in the tubular extension 10 of the worm 95 sector casing 2^a. From this arrangement there results the independence of the adjustments of the two scales, constituting the essence of the invention. The operation of this arrangement is as follows:—

In case of visible targets, the target seen under a certain ground angle is sighted by 100 means of the telescope so that the optical sight line is inclined to the ground at an angle. This therefore need not be further considered for which reason the ground angle scale 6^a, 8^a is adjusted to zero by means 105 of the marks 8^c and 7^a. This is done by drawing out the drum 8 by means of its grasping edge, the spring being overcome

and the radial teeth of the rings 12 and 13 being brought out of engagement with each other. Then the firing angle, corresponding to the distance of the target (that is to say the angle between the sight line and the axis of the bore of the gun) is adjusted by simultaneously turning the grasping edges 6 and 8^a held, in engagement by the pressure of the spring 11, thus adjusting the mark 9^a directly to the distance of the target along the distance scale 8^a. By operating the elevating screw of the machine gun, the target is brought into the sight line, whereby the axis of the bore is brought to the required total elevation.

On firing on targets hidden from sight, however, the ground angle determined in any suitable way, is indicated on the scale 6^a and 8^a by means of the marks 8^a and 7^a, 20 by turning the two grasping edges 6 and 8^a, after the rings 12 and 13 have been disengaged from each other. Then by simultaneously turning the two grasping edges the distance of the target, determined in any 25 suitable manner, is adjusted on the distance scale 8^a by means of the mark 9^a, and then by means of the elevating screw of the machine gun, the longitudinal water level provided on the telescope is adjusted to the horizontal.

30 In view of the shocks, produced on firing, it is desirable to lock the parts in the position to which they are adjusted as is indicated in the constructional form shown in Figs. 6 and 7. In these views the ring 12^a screwed fast in the drum 8 bears, with its face flat against the face of the supporting ring 13^a, secured on the worm spindle, whereas the sleeve 6 secured on the square part of the worm spindle 5 carries 40 on its periphery, fine spur teeth 6^a into which engage the internal teeth of the axially movable handle sleeve G. These internal teeth, however, simultaneously engage, completely into similar external teeth 45 8^a of the drum 8 so, that the latter is positively clutched to the sleeve 6. The hub of the handle sleeve G is hollow and encloses the pressure spring 11 which bears on the one hand against one end face, of 50 the hollow hub and on the other hand against a plate 5^b, resembling a piston on the worm spindle, and thus holds the handle sleeve in the clutching position shown.

55 For adjusting the ground angle on the scale 6^a and 8^a, by means of the marks 8^a and 7^a, the handle sleeve 9 is pulled out until the teeth of the drum 8 becomes fully visible whereby the engagement with the sleeve 6 is released, so that the two parts are now free to rotate relatively to each other. After the adjustment of the scales, the internal teeth of the handle sleeve G are pushed over the external teeth of the drum 8 with the assistance of the spring, whereby

the adjustment of this scale is locked. In 65 order to also lock the adjustment of the elevation angle on the scale 8^a by the mark 9^a, the annular front edge of the handle sleeve G is provided with radial teeth G^a into which the knife edge S of a lock bolt 70 12 engages. This bolt is secured to the drum casing 10. Therefore the adjustment of this firing angle may be effected independently of the adjustment of the ground angle, the handle sleeve being drawn out to 75 the slight extent of the axial length of the radial teeth G^a.

Of course the scale 6^a, 8^a may also be used as the firing angle scale and the scale 8^a as the ground angle scale. 80

What I claim is:

1. In a breech sight for ordnance and machine guns the combination of a telescope and a telescope carrier with a single gearing comprising a worm and a worm wheel sector for turning the telescope around a horizontal axis perpendicular to the sight line, means for indicating the ground angle and means for indicating the firing angle, each of such means comprising a scale and a 90 mark associated thereto, an inner sleeve secured to the said worm, an outer sleeve surrounding such inner sleeve, a releasable clutch interposed between the said sleeves, screw threads on such sleeves, nut sectors 95 engaging into the screw threads of the sleeves, one of such nut sectors projecting through a longitudinal slot in the said outer sleeve and the other nut sector projecting through a longitudinal slot of a part of the 100 carrier.

2. In a breech sight for ordnance and machine guns the combination of a telescope and a telescope carrier with a single gearing comprising a worm and a worm wheel sector for turning the telescope around a horizontal axis perpendicular to the sight line, means for indicating the ground angle and means for indicating the firing angle, each of such 105 means comprising a scale and a mark associated thereto, an inner sleeve secured to the said worm, an outer sleeve surrounding such inner sleeve, a releasable clutch interposed between the said sleeves, screw threads on such sleeves, nut sectors engaging 110 into the screw threads of the sleeves, one of such nut sectors projecting through a longitudinal slot in the outer sleeve and the other nut sector projecting through a longitudinal 115 slot of a part of the carrier, a grasping sleeve 120 adapted to move axially and operatively connected with the said clutch and a lock bolt secured to the carrier of the back sight and adapted to engage said grasping sleeve. 125

In testimony whereof I have affixed my signature.

KARL PETSCHENIG.
